UNITED STATES PATENT OFFICE.

HARRY B. DEMPSEY, OF NEW YORK, N. Y.

RECUPERATIVE FURNACE.

Application filed November 5, 1920. Serial No. 421,870.

To all whom it may concern:

Be it known that I, HARRY B. DEMPSEY, a citizen of the United States, and a resident of New York city, in the county of 5 New York and State of New York, have invented certain new and useful Improvements in Recuperative Furnaces, of which the following is a specification.

My invention relates to apparatus for 10 claiming heat from the waste gases of industrial heating furnaces, gas retorts, etc., the function of the apparatus being to transfer a large percentage of heat contained in the flue gases to the fuel combustion air, 15 thereby conserving fuel, promoting combustion, and making possible the use of fuels of low heat value.

The primary object of this invention is to 20 provide a recuperator of such structural form that will eliminate the leakage of combustion air from air passages to flue gas passages, and also of such form that will 25 secure the greatest possible contact between the air and the surfaces heated by the waste gases.

A further object is to simplify the component parts of the recuperator and to reduce manufacturing and construction costs.

In the accompanying drawings, Fig. 1 30 is a vertical longitudinal section on the line 1—1 of Fig. 2, of a billet heating furnace embodying the invention; Fig. 2 is a cross section of the same taken on the line 2—2 of Fig. 1; Fig. 3 is a perspective view of a 35 flue tile utilized in my construction of recuperator; Fig. 4 is a perspective view of the parts of a modified construction of the same; Fig. 5 is a perspective view of a lock-joint tile utilized by me in connection with 40 the tiles of the character shown in Figs. 3 or 4, in building up my new recuperator; and Fig. 6 a perspective view of the assembled recuperator.

In the drawings I have shown my improvements as applied to a billet heating furnace, but it is understood that my invention is not restricted to employment in connection with any particular type of furnace, it being applicable to any form where 50 it is desirable or necessary to heat the combustion air.

In the form shown, 1 designates the combustion ports and 2 the heating chamber. The waste combustion gases pass downward 55 through flues 3 to chamber 4 and thence to flue 5, and from flue 5 the gases enter a

series of flues or conduits 6, passing thence to flue 7 and returning through flues 8 where access is had to stack flue 9.

Air is admitted to flue 10 which extends 60 the full length of recuperator, and contains passageways to flues 11. The air passes back and forth through flues 11 in the directions indicated by arrows, and enters flue 12. From flue 12 the air in a highly heated state 65 finds its way into uptakes 13 and passes into and intermingles with the fuel in the combustion ports 1.

During the sojourn of the waste combustion gases through the system of flues 6 and 70 8, a large percentage of the heat contained in same is absorbed by the containing walls, and then imparted to the air currents in flues 11. The air flows in counter direction 75 to the waste combustion gases and leaves the recuperator at its hottest part, thus receiving the maximum preheat.

The recuperator is composed of tubular blocks 20 (Fig. 3) and lock joint tiles 22 (Fig. 5) and said blocks 20 are formed with 80 flanges or tongues 21 at both ends in two opposite sides. The tubular blocks 20 are laid end to end and side by side forming rows of extended flues. The rows of blocks 85 are built in tiers, and are separated, one tier from the other, by means of the lock joint tiles 22. The spaces between each tier form another system of flues at right angles to the first. The lock joint tiles in addition to forming separators for the tubular blocks 90 serve to lock the tubular blocks together so that the joints cannot separate due to vibration or expansion and contraction. The blocks 20 and tiles 22, all being commonly known as tiles, are preferably made of refractory material, but any other suitable material may be employed. As shown in 95 Figs. 5 and 6 the tiles 22 are formed in their upper and lower faces with longitudinal grooves 23 adapted to receive the abutting 100 flanges on adjacent ends of the blocks 20.

The flues 6 and 8 are preferably used for the waste gases, and flues 11 for the combustion air, but this whole position may be reversed and flues 6 and 8 used for the combustion air and flues 11 for waste gases.

The accompanying drawings show the recuperator located under the furnace hearth, but it may be placed at any other convenient place, depending upon the furnace design 110 and conditions of installation.

The blocks 20 instead of being in one in-

tegral piece, may be formed of two matching interlocking sections 24, 25, as indicated in Fig. 4.

The surface of the bore in the tubular blocks 20 may contain lugs, ribs or corrugations, should such features add to the efficiency of the recuperator.

In the above description I have shown a recuperator built up of a system of parallel 10 flues through which the waste products of combustion are allowed to circulate on their way to the atmosphere, and another system of flues at right angles to the first system in which the air currents circulate. The tiles 15 are of such form that they will be locked together in a manner that will insure the whole mass expanding and contracting together as a unit, thus making possible permanently tight joints and overcoming objections in 20 other forms of recuperators.

What I claim as my invention and desire to secure by Letters Patent, is:

1. A recuperator of the character described composed of two systems of alternating 25 tiers of blocks and each system comprising in each tier a plurality of parallel rows of horizontally disposed blocks, the blocks of one system being tubular and in the layers thereof arranged in side by side and end to 30 end abutting relation and formed integrally at the ends of their upper and lower sides with oppositely projecting flanges, and the blocks of the other or second system being solid and arranged in rows at right angles to 35 the blocks of the first system and in end to end abutting relation and spaced-apart side

relation and formed with upper and lower grooves snugly receiving and interlocking with the end flanges on the blocks of the first system, the grooves in the intermediate 40 blocks of the second system being adapted to receive the contiguous flanges of the adjacent abutting ends of the blocks of the first system.

2. A recuperator of the character described composed of two systems of alternating tiers of blocks and each system comprising in each tier a plurality of parallel rows of horizontally disposed blocks, the blocks of one system being tubular and in the layers thereof arranged in side by side and end to 45 end abutting relation and formed integrally on their abutting ends with oppositely projecting flanges, and the blocks of the other or second system being solid and arranged in rows at right angles to the blocks of the first system and in end to end abutting relation and spaced-apart side relation and the intermediate blocks of said second system being formed with longitudinal 50 grooves snugly receiving and interlocking with the contiguous abutting flanges on upper and lower blocks of the first system, said intermediate blocks of the second system thus serving to create flues between them and 55 also to couple together the adjoining ends of the adjacent tubular blocks of the first system.

Signed at New York city, in the county of New York and State of New York, this 4th 60 day of November, A. D. 1920.

HARRY B. DEMPSEY,
